CLAIM

The ornamental design for a suspended support for a projector mounting rack, as shown and described.

DESCRIPTION

FIG. 1 is a perspective view showing my new design for a suspended support for a projector mounting rack; FIG. 2 is a front elevational view thereof, the rear elevational view thereof being substantially the same; FIG. 3 is a left side elevational view thereof; FIG. 4 is a right side elevational view thereof; and, FIG. 5 is a top plan view thereof, the bottom plan view thereof being substantially the same. The broken line showing of the rack and supports therefor is for illustrative purposes only and forms no part of the claimed design.
